DESIGN FOR A PIANO OR SIMILAR ARTICLE

Alexander P. Brown, Beechhurst,
Long Island, N. Y.

Application January 15, 1946, Serial No. 125,554

Term of patent 3½ years

(Cl. D56—9)

To all whom it may concern:

Be it known that I, Alexander P. Brown, a citizen of the United States and resident of Beechhurst, Long Island, county of Queens, and State of New York, have invented a new, original, and ornamental Design for a Piano or Similar Article, of which the following is a specification, reference being had to the accompanying drawing, forming part thereof, and in which Fig. 1 is a front elevational view of a piano or similar article showing my new design; Fig. 2 is a side elevation thereof; Fig. 3 is a top plan view with cover closed, and Fig. 4 is a rear elevational view.

I claim:

The ornamental design for a piano or similar article, as shown.

ALEXANDER P. BROWN.
